Assignor to

Edward C. Sampson of New York City

Letters Patent No. 2441, Date issued 25th 1866.

Design for a floor Oil Cloth Pattern.

The Schedule referred to in these Letters Patent and making part of the same.

To all whom it may concern:

Be it known that I, Charles St. Meyer of the Town of Bergen, County of Hudson and State of New Jersey, have invented or produced a new, original and ornamental Design or Pattern for Floor Oil Cloths, Carpets and other Fabrics; and I do hereby declare that the accompanying drawing marked and designated as Sheet 1, No. 2, fully represents said design and is sufficient without further aid, to enable any person skilled in the art to which it appertains to repeat it for practical use. The colors and the arrangement of them may, in the use of the design be varied to suit the taste or the fancy of the user, or manufacturer of articles ornamented by said design.

This design may be of any size or colors in kind or number, or in any contrast or blending of colors of light and shade.

I claim as new, and desire to secure by Letters Patent, of the United States, the Design for Floor cloth, Carpet &c. as shown and described.
